Primary Examiner — Sharon S Oum

(57) **CLAIM**

The ornamental design for fan, as shown and described.

DESCRIPTION

FIG. 1 is a front view of the fan showing my new design;
FIG. 2 is a back view thereof;
FIG. 3 is a left side view thereof;
FIG. 4 is a right side view thereof;
FIG. 5 is a top view thereof;
FIG. 6 is a bottom view thereof;
FIG. 7 is a perspective view thereof; and,
FIG. 8 is another perspective view thereof.
The broken lines show portions of the fan that form no part of the claimed design.
